UNITED STATES PATENT OFFICE.

CHARLES THEOFLUS HOLMAN, OF MEADVILLE, PENNSYLVANIA.

WRENCH.

No. 867,272.

Specification of Letters Patent.

Patented Oct. 1, 1907.

Application filed June 28, 1907. Serial No. 381,487.

To all whom it may concern:

Be it known that I, CHARLES THEOFLUS HOLMAN, a citizen of the United States, residing at Meadville, in the county of Crawford and State of Pennsylvania, have invented new and useful Improvements in Wrenches, of which the following is a specification.

This invention relates to wrenches, the object of the invention being to provide a device of this character having simple and effective means for obtaining a rough or primary adjustment and a secondary or final adjustment, by virtue of which latter feature the wrench is adapted to firmly grip an object without possibility of slippage.

In the drawings accompanying and forming part of this specification I show in detail one form of embodiment of the invention which, to enable those skilled in the art to practice the same, will be set forth in detail in the following description, while the novelty of the invention will be included in the claims succeeding said description.

Referring to said drawings: Figure 1 is a perspective view of said wrench. Fig. 2 is a longitudinal sectional view of the same, and Fig. 3 is a detail view in perspective of the pawl shown in the preceding figures, and operating spring therefor.

Like characters refer to like parts throughout the several figures of the drawings.

The wrench shown involves in its make-up a shank or main portion as 2 represented as terminating at one end in the head or fixed jaw 3. These parts may be and preferably are as usual integral.

The movable or slideable jaw is denoted by 4 and it is provided with a sleeve as 5 inclosing and longitudinally movable upon the shank or main portion 2.

The shank 2 is shown as having throughout its entire length the groove or channel 6 in which is represented as endwise-movable the normally-stationary rack-bar 7, the teeth of which are engageable by one or more teeth on the pawl or detent 8. This detent is shown as partially inclosed by the sleeve 5 and as terminating at its upper end in a rounded head as 9 fitting in a correspondingly-shaped socket as 10 in the under side of the movable jaw 4. Said pawl 8 is shown as provided with a pin 11 surrounded by the coiled push-spring 12 bearing against the pawl 8 and inner surface of the sleeve 5. The function of this spring 12 is to force the teeth of the pawl 8 into engagement with the teeth of the rack-bar 7 and to also maintain such engagement. The pawl 8 is shown as being in engagement with the rack-bar 7 to hold the jaw 4 in an adjusted position. To change the adjustment the pawl 8 is swung outward sufficiently to disengage its teeth from those of the rack-bar 7, after which the jaw 4 can be moved toward or from the companion jaw and, when the adjustment is effected, the pawl will be released and the spring 12 will move the teeth thereof into engagement with those of the rack-bar to hold the adjustment. To facilitate the operation of the pawl 8 it may, as shown, be provided with an outwardly curved finger-piece as 13.

60

A thimble-like nut 14 is shown as threaded on to the outer end of the shank 2, and the purpose of this nut is to advance the rack-bar 7 in opposition to a spring as 15 located in the channel 6 and active against said bar and head or jaw 3, respectively. The spring, as 65 will be clear, tends at all times to impart a retracting or outward longitudinal movement to the bar 7. The outer end of the bar 7 is shown as having a shoulder or enlargement as 16 between which and the bottom of the nut 14 several rollers as 17 may be interposed, 70 and these rollers preferably take the form of balls so as to provide for an anti-frictional relation between the nut 14 and bar 7. Prior to the adjustment of the wrench to an object, assuming that it is desired to use both adjustments thereof, the nut 14 is run out, after 75 which the jaw 4 is operated to grip the object to be turned. It will be assumed, of course, that the grip is a free one and that it is desired that the same be tight, and this is the purpose of the two adjustments. To secure a tight grip upon the object the nut 14 is 80 turned to the right, thereby acting against the inclosed head 16 to impart an inwardly-advancing or longitudinal movement to the bar 7 and, owing to the connection between the bar and the jaw 4, the latter is correspondingly moved to effect the desired object. I provide means to prevent the nut 14 from being accidentally wholly unscrewed from the body portion 2 and thereby lost, and the means illustrated for this purpose will now be set forth. A rod 20 is shown as extending along a channel as 21 formed in the outer 85 end of the rack-bar 7, the outer end of said channel being open and the rod projecting outwardly through said open end through a perforation in the nut 14 and having a head 21' bearing against the bottom of a concavity formed in the under side of said nut. The upper 90 or inner end of the rod has a hook or literally bent portion as 22 adapted to travel in a groove 23 extending longitudinally of the body portion 2, the hook being adapted to engage the ends of the said groove or slot 23 when the nut 14 is at the limit of its opposite movements. To the under side of the nut 14 is pivoted a flap as 24 which when closed is adapted to extend across the head 21'. The rod 20, as will be understood, follows the rack-bar 7 as the latter is moved endwise by 95 the nut 14, and it serves by abutting against the lower end of the groove or slot 23 to prevent the complete separation of the nut from said body portion.

100

A number of variations may be adopted within the scope of my claims. For instance, while I show the bar 7 as spring-actuated in one direction, it is not 110 essential that I provide such a spring as 15 nor locate it in the place indicated, nor is it necessary that I

provide a spring as 12. I mention these as several details which may be deviated from within the boundaries of my appended claims.

What I claim is:

- 5 1. A wrench embodying a shank having a fixed jaw and also having a longitudinally disposed channel, a rack-bar fitted in said channel, for end-wise movement, a thimble-like nut threaded onto the outer end of the shank and operative for moving the rack-bar in an end-wise direction, a 10 slideable jaw on the shank, a pawl movable with the slideable jaw and adapted to engage the toothed portion of the rack-bar, and a series of anti-friction rollers bearing against the bottom of the said nut and also bearing against the outer end of said rack-bar.
- 15 2. A wrench embodying a shank provided with a fixed jaw, a bar carried by and movable longitudinally of said shank, a jaw slideable with respect to said bar, means connected with said slideable jaw for fixedly connecting the same with said bar, a nut in threaded relation with the

shank for imparting an endwise movement to said bar, 20 and a rod connected with the nut, extending longitudinally of said bar and provided with a lateral offset, the shank having a longitudinal slot to receive said offset.

3. A wrench embodying a shank provided with a fixed jaw, a rack-bar movably connected with said shank, a 25 slideable jaw on said shank, a pawl on the slideable jaw to engage the teeth of the rack-bar, a nut in threaded relation with the shank for imparting an advancing movement to said bar, and a rod connected with the nut, extending longitudinally of said rack-bar, and provided with a lateral 30 offset, the shank having a longitudinal slot to receive said offset.

In testimony whereof I have hereunto set my hand in presence of two subscribing witnesses.

CHARLES THEOFIUS HOLMAN.
